GARMENT CLASP

Ludwig Stark, North Bergen, N. J.

Application May 20, 1936, Serial No. 80,697

3 Claims. (Cl. 24—250)

This invention relates to new and useful improvements in a garment clasp.

The invention has for an object the construction of a garment clasp which is characterized by a pair of body members pivotally connected intermediate of their ends and resiliently urged together and associated with a locking member disposed between the tail ends of said body members and operating in a novel fashion.

10 A further object of the invention resides in an arrangement whereby the locking member comprises a lever which is pivotally mounted between flanges formed on one of the body members.

15 Still further the invention also contemplates the provision of an element adjustably mounted on the locking member and adapted to engage one of the jaws for locking the jaws in another position.

20 A still further object of the invention is to provide a safety snap arrangement for the locking member.

Another object of the invention is the construction of a device as mentioned which is simple and durable and which may be manufactured and sold at a reasonable cost.

25 For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

30 Fig. 1 is a perspective view of a garment clasp constructed according to this invention.

Fig. 2 is a perspective view of a garment clasp shown in Fig. 1 but illustrated upside down.

35 Fig. 3 is a view similar to Fig. 2 but illustrating the clasp in open position.

Fig. 4 is a sectional view taken on the line 4—4 of Fig. 1.

Fig. 5 is a transverse sectional view taken on the line 5—5 of Fig. 4.

40 Fig. 6 is an end elevational view of the clasp, for example, seen from the left hand end of Fig. 4.

Fig. 7 is an elevational view looking in the direction of the line 7—7 of Fig. 3.

45 Fig. 8 is a perspective view similar to Fig. 2 but illustrating a modified construction.

Fig. 9 is a sectional view taken on the line 9—9 of Fig. 8.

50 Fig. 10 is a similar view to Fig. 4 but illustrating a still further modification of the device.

The garment clasp, according to this invention, comprises a pair of body members 10 and 11 respectively, pivotally connected intermediate of their ends by a rivet 12. A resilient means is arranged for urging the jaw members into open 5 position as shown in Fig. 3. A locking member 14 is mounted on one of said jaw members and is disposed partially between the tail ends of the jaw members and is movable into a position to hold the jaw members closed. 10

The jaw member 11 has flanges 11^a formed at its sides, and a flange 11^b formed at its front end. The jaw member 10 has flanges 10^a formed at its sides and a flange 10^b formed at its front end. The jaw member 10 is slightly smaller 15 than the jaw member 11 so as to be disposed therein; that is, the side flanges 10^a are in intimate contact with the inner faces of the side flanges 11^a. The rivet 12 extends completely across the flanges 11^a and consequently through 20 the flanges 10^a. A spring 15 is mounted upon the intermediate exposed portion of the rivet 12 and acts between the jaw members to urge the jaw members open.

The locking member 14 comprises an inner 25 U-shaped portion 14^a which has a trunnion 14^b, the elements of which pivotally engage the flanges 11^a. The locking member 14 also has an external handle portion which is formed with a slot or other opening 14^c. The jaw member 30 10 has an overhanging curved tail portion 10' which is adapted to engage against the central bent portion 14^a when the handle 14 is in the same plane with the jaw members, and the jaw members necessarily must be closed. If the handle 14 is pivoted clockwise (as illustrated in Fig. 4) the portion 14^a of the handle will be swung out from contact between the tail portions of the jaw members and the jaw members will be opened up to the positions shown by the dotted 40 lines in Fig. 4, or the full lines in Figs. 3 and 7.

In Figs. 8 and 9 a modified form of the invention has been disclosed in which an arrangement is provided for holding the jaw members closed to one or another condition. More specifically, 45 there is a transverse element 16 which is adjustably mounted on the locking member 14 and which may be moved to an inoperative position, as shown in Fig. 8, or to an operative position as shown in Fig. 9. The member 16 has several projecting rivets 17 engaging through slots 18 formed in the locking member 14. These rivets and slots limit the element 16 to be shifted along upon the locking member to and from the positions shown in Figs. 8 and 9. 50 55

The garment clasp in this form of the invention is very similar to that previously described and the same parts may be recognized by the same reference numerals. The jaw member 10 is formed with a pressed-out portion 10^a in the tail end 10' thereof into which the element 16 may be engaged. When the element 16 is in the inoperative position, as shown in Fig. 8, the jaw members will be held closed as shown in Fig. 4. When the element 16 is in the position shown in Fig. 9 the jaw elements are forced closed with the outer ends thereof closer together.

In Fig. 10 a still further modified form of the invention has been disclosed, in which a safety snap arrangement is provided by forming a transverse bead 11^c on the body member 11, near the opposite end to the flange 11^b. With this arrangement, the free end 14^d of the U-shaped portion 14^a is permitted to snap past the bead 11^c, thereby keeping the locked member 14 more securely in locking position.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:—

1. In a garment clasp, comprising a pair of jaw members pivotally connected intermediate of their ends, a locking member mounted on one of said members and disposed between the tail

ends of said members and movable to a position to hold said jaw members closed, said locking member having an inner U-shaped end with a trunnion the elements of which pivotally engage one of said members, and one of said jaw members having a tail portion curved to conform with and engaging and terminating against the bend of said U-shaped portion when the locking member is in the same plane with the jaw members, said U-shaped portion being adapted to be moved out of position between the tail ends of said members for opening said members.

2. A garment clasp, comprising a pair of jaw members pivotally connected intermediate of their ends, resilient means urging said jaw members open, a locking member mounted on one of said members and disposed between the tail ends of said members and movable to a position to hold said jaw members closed, and an element adjustably mounted on said locking member and adapted to be moved to a position to engage against one of said tail ends.

3. A garment clasp, comprising a pair of jaw members pivotally connected intermediate of their ends, resilient means urging said jaw members open, a locking member mounted on one of said members and disposed between the tail ends of said members and movable to a position to hold said jaw members closed, and an element adjustably mounted on said locking member and adapted to be moved to a position to engage against one of said tail ends, said element being supported by rivets engaging longitudinal slots formed in said locking.

LUDWIG STARK. 35
